CLAIM

The ornamental design for an overlay cap for bottles, as shown and described.

DESCRIPTION

FIG. 1 is a perspective view of an overlay cap for bottles showing my new design;

FIG. 2 is a top view thereof;

FIG. 3 is another perspective view thereof;

FIG. 4 is a front elevational view thereof; and,

FIG. 5 is a bottom view thereof.

A rear elevational view, a left side view and a right-side view are omitted since the rear elevational view, the left side view and the right-side view are identical with the front elevational view.
